Filed July 5, 1963, Ser. No. 293,067
5 Claims. (Cl. 308—38)

This invention relates, generally, to railway car journal boxes and it has particular relation to combined lubricators and journal stops for the axle journals mounted therein.

Among the objects of this invention are: To provide in a new and improved manner for mounting journal stops on a lubricating pad employed for transporting lubricant to the axle journal mounted in conventional manner in a railway car journal box; to arrange for applying the journal stops after the lubricating pad has been inserted in the journal box; to hold the journal stops in operative position on the lubricating pad in such manner that they can be readily applied and removed; to slot the upwardly extending ends of the lubricating pad in order to facilitate the application of the journal stops after the pad has been installed; to provide retainer pins extending through the ends of the lubricating pad and the journal stops in parallel relation to the axle journal; to employ a pair of spaced apart journal stops at each end of the lubricating pad; to interconnect each pair of journal stops to the end that they can be inserted and removed as a unit; and to reinforce the lubricating pad by expanded metal mesh formed integrally therewith.

In the drawings:

FIG. 1 is a vertical sectional view taken generally along the line 1—1 of FIG. 2 and showing one embodiment of the combined lubricator and journal stop applied in a journal box of conventional construction which forms an integral part of a car truck side frame, the axle journal being shown in broken outline and parts of the combination lubricator and journal stop being shown likewise in order to more clearly illustrate the details of construction.

FIG. 2 is a vertical sectional view taken generally along the line 2—2 of FIG. 1.

FIG. 3 is a perspective view showing the application of the combination lubricator and journal stop with the car axle omitted.

FIG. 4 is a perspective view showing the details of construction of the combination lubricator and journal stop, the lubricator being constructed generally as shown in U.S. Patent No. 3,033,625, issued May 8, 1962, to J. A. Schroeder.

FIG. 5 is a perspective view of a modified construction for the lubricating pad shown in FIG. 4.

FIG. 6 is a vertical sectional view of the reinforced lubricating pad shown in FIG. 5 and showing at an enlarged scale the reinforcing expanded metal.

FIG. 7 is a view, similar to FIG. 4, showing certain modifications in the construction of the journal stops and showing a lubricating pad construction generally as illustrated in U.S. Patent No. 2,975,009, issued Mar. 14, 1961, to S. G. Bair.

Referring now particularly to FIGS. 1 and 2 of the drawings, it will be observed that the reference character 10 designates, generally, one end of a railway car axle of conventional construction which includes an axle journal 11 having an end collar 12 at the outer end and at the inner end a shoulder 13. The longitudinal axis of rotation of the railway car axle 10 is indicated at 14 in FIG. 1.

In accordance with conventional practice a railway

car journal box, indicated generally at 15, is provided for receiving the axle journal 11. It includes a top wall 16, side walls 17—17 and a curved bottom wall 18 which at its outer end has a curved bottom end wall 19. The conventional lid opening 20 is provided, the lid not being shown. At the other end of the journal box 15 there is dust guard well 21 which is formed between vertical walls 22 and 23. The hub portion 24 of the railway car axle 10 which terminates in the shoulder 13 extends through that portion of the journal box 15 which provides the dust guard well 21. It will be understood that the lower portion of the journal box 15 has a filling of lubricant therein to the level indicated by the broken line shown at 26 in FIG. 1.

Extending inwardly from the side walls 17—17 at the upper portions thereof are wedge guide columns 27—27 which are provided in accordance with conventional practice for locating the wedge and journal bearing through which the load is transmitted from the truck side frame 20 to the axle journal 11. Since the wedge and journal bearing are of conventional construction, they are not shown.

It is desirable to provide for transporting the lubricant in the lower portion of the journal box 15 to the surface 25 of the axle journal 11. In addition it is desirable to limit the movement of the axle journal 11 with respect to the side wall 17—17. For these purposes a combination lubricator and journal stop, indicated generally at 28, is employed. The details of construction are shown more clearly in FIG. 4 where it will be observed that a lubricating pad 29 of felt is provided having thereon longitudinally extending upstanding resilient blocks 30, 31 and 32 covered by fabric 33 which serves as a wick to transport the lubricant to the surface of the axle journal 11. 35 As described in more detail in the Schroeder patent above referred to the blocks 30 and 31 are of the same height and length while the block 32 is longer and higher since it is positioned adjacent the shoulder 13 and it is desired to provide a seal against the passage of the lubricant beyond the shoulder 13.

In accordance with this invention journal stops 34—34 are provided in slots 35—35 having semi-circular bottoms 36—36 located in the ends 37—37 of the pad 27. As indicated in the Schroeder patent the pad 29 is formed of felt or other lubricant absorbent material. The journal stops 34—34 are preferably cylindrical in shape and are formed of non-ferrous metal such as brass. They are inserted in the slots 35—35 after the lubricating pad 29 with the blocks 30, 31 and 32 covered by the fabric 33 mounted therein has been inserted in position in the journal box 15 underneath the axle journal 11.

In order to hold the journal stops 34—34 in operating position in the slots 35—35 retaining pins 38—38 are provided in aligned openings 39—39 in the ends 37—37 55 of the pad 29 and through openings 40 in the journal stops 34—34.

When it is desired to remove the journal stops 34—34 for the purpose of replacing them or for replacing the lubricating pad 29 and parts attached thereto, the retaining pins 38—38 can be withdrawn readily. This permits removal of the journal stops 34—34. Thereafter the lubricating pad 29 and parts mounted thereon can be flexed around the end collar 12 and removed from the journal box 15. Such action is facilitated by first removing the wedge and journal bearing from the journal box 15 and then jacking the axle 10 to provide greater clearance between its underside and the lower portion of the journal box 15.

It is desirable to position the ends 37—37 of the lubricating pad 29 as illustrated in FIG. 1 intermediate the inner sides of the side walls 17—17 and the diametrically

opposite sides of the axle journal 11. In order to provide a more rigid construction for holding the journal stops 34—34 in operative position the construction shown in FIGS. 5 and 6 is provided. Here it will be observed that the reference character 41 designates, generally, a reinforced lubricating pad which is provided with a reinforcing material in the form of expanded metal mesh for 42. In other respects the pad 41 is identical in construction with the pad 29. The expanded metal mesh 42 is of conventional construction and may be formed of non-ferrous corrosion resisting metal such as brass or copper. The felt is formed integrally with the expanded metal mesh 42 and is preferably positioned on both sides as shown in FIG. 6. The upper layer is shown at 43 and the bottom layer is shown at 44. While the reinforced lubricating pad 41, because of the provision of the expanded metal mesh therein, is not as flexible as the felt lubricating pad 29, still it is sufficiently flexible to permit insertion in the bottom of the railway car journal box 15 in the manner described. Also it can be removed as above outlined.

FIG. 7 shows another embodiment of the combination lubricator and journal stop. Here the reference character 45 designates, generally, a combination lubricator and journal stop in which are incorporated certain features of construction of the journal lubricator described in the Bair patent above referred to. It includes a lubricating pad 46 which may be either in construction to the pad 29 or the reinforced lubricating pad 41 previously described. On the pad 46 are transversely extending resilient blocks 47 that are covered by a fabric 48 for the purpose of transporting the lubricant from the bottom of the railway car journal box to the surface of the axle journal 11.

With a view to facilitating the application of the journal stops 34—34 to the slots 35—35 at the ends 37—37 of the pad 46, the journal stops 34—34 are interconnected by a connecting bar 49. If desired, the connecting bar 49 can be formed integrally with the journal stops 34—34. It is located adjacent the end portions thereof which are juxtaposed to the diametrically opposite sides of the axle journal 11. The reason for this arrangement is to permit the connecting bar 49 to clear the wedge guide column 27 when the journal stops 34—34 are applied as a unit to the respective end 37 of the combination lubricator and journal stop 45. For holding the journal stops 34—34 in operative position at the ends of the lubricating pad 46 the retaining pins 38—38 can be employed in the manner previously described.

What is claimed as new is:

1. In a railway car journal box construction, a journal box having spaced vertical side walls with an axle journal in spaced relation therebetween, top and curved bottom walls interconnecting said side walls above and below said axle journal respectively, and a lubricant in said journal box; the improvement which comprises:

(a) a lubricant absorbing pad overlying said curved bottom wall, extending upwardly past diametrically opposite sides of said axle journal and having slotted ends,

- (b) resilient block means extending upwardly from the upper side of said pad,
- (c) a fabric overlying said resilient block means to transport the lubricant to the surface of said axle journal,
- (d) journal stop means in said slotted ends of said pad interposed between the respective side walls of said journal box and the diametrically opposite sides of said axle journal to limit the movement thereof with respect to said side walls, and
- (e) retaining means extending in parallel relation to said axle journal through said slotted ends of said pad and through said journal stop means to hold said journal stop means in said slotted ends,
- (f) said journal stop means projecting beyond opposite sides of the respective ends of said pad whereby said slotted ends are spaced from the respective side walls of said journal box and the diametrically opposite sides of said axle journal.

2. The invention, as set forth in claim 1, wherein the retaining means includes means for facilitating the detachment of the same from said journal stop means and from said slotted ends of said pad whereby said journal stop means can be applied to said slotted ends after said pad is inserted in the journal box.

3. The invention, as set forth in claim 1, wherein each end of said pad has two upwardly opening slots.

4. The invention, as set forth in claim 3, wherein:

- (a) each slot has a semicircular bottom, and
- (b) said journal stop means includes a journal stop received in each slot and having a circular cross section.

5. The invention, as set forth in claim 3, wherein said journal stop means includes a plurality of journal stops, said journal stops at each end of the pad being rigidly interconnected by said retaining means to provide a unitary construction that is insertable and removable as a unit.
